US0D1104481S

(12) **United States Design Patent** (10) **Patent No.:** **US D1,104,481 S**
(45) **Date of Patent:** **** Dec. 9, 2025**

(54) **TOOTHBRUSH**

(71) Applicant: **The Gillette Company LLC**, Boston, MA (US)

(72) Inventors: **Uwe Jungnickel**, Königstein (DE); **Dominik Langhammer**, Frankfurt (DE); **Christine Hallein**, Frankfurt (DE); **Jens Störkel**, Frankfurt (DE)

(73) Assignee: **The Gillette Company LLC**, Boston, MA (US)

(**) Term: **15 Years**

(21) Appl. No.: **29/895,038**

(22) Filed: **Jun. 16, 2023**

Related U.S. Application Data

(62) Division of application No. 29/762,790, filed on Dec. 18, 2020, now Pat. No. Des. 1,014,095.

(30) **Foreign Application Priority Data**

Jul. 2, 2020 (WO) WIPO96062

(51) **LOC (15) Cl.** **04-02**

(52) **U.S. Cl.** **D4/110**

(57) **CLAIM**

The ornamental design for a toothbrush, as shown and described.

DESCRIPTION

FIG. 1 is a perspective view of a toothbrush;

FIG. 2 is a front view thereof;

FIG. 3 is a left-side view thereof;

FIG. 4 is a rear view thereof;

FIG. 5 is a right-side view thereof;

FIG. 6 is a top view thereof; and,

FIG. 7 is a bottom view thereof.

The evenly spaced broken lines depict portions of the toothbrush that form no part of the claimed design.

1 Claim, 2 Drawing Sheets
